DOUBLE SEAL SIDING

Herbert T. Seymour, Easton, Md., assignor to
A. R. Exner, Chicago, Ill.

Application November 28, 1942, Serial No. 467,218

3 Claims. (Cl. 20—5)

The present invention concerns new lap siding, clap board, shingles, whether of wood or any composition or molded material or the like, which are used as an outer covering for houses and other buildings. It is an object of the invention to provide a siding which is wind and weather proof and will prevent insects and the like from entering.

It is an object of the invention to provide a clap board or lap siding which has three lines of wind and weather seal. It is an object of the invention to provide a clap board or lap siding which has no exposed nail holes nor any need for putty.

It is an object of the invention to provide siding or clap board which is firmly held at both top and bottom and give the lap desired.

It is an object of the invention to provide a siding which greatly reduces the cost of upkeep.

It is an object of the invention to provide siding which when used in short pieces as between doors and windows, danger of split ends and the like requiring special treatment is eliminated.

It is the object of the invention to provide a double seal strip which is reversible so as to place siding up under windows and doors and over windows and doors.

It is the object of the invention to provide a siding that still retains its colonial appearance.

It is the object of the invention to provide a special double cutter which cuts both the double end groove and shoulders with one operation.

In the drawing

Fig. 1 is a perspective of one form of the siding in place.

Fig. 2 is a fragmentary perspective detail of a portion of the siding.

Fig. 3 is a perspective detail of a wind and weather sealed strip.

Fig. 4 is a perspective detail of a double cutter which cuts both the double end groove and shoulders with one operation.

In the drawing like numbers refer to like parts throughout.

Means or studding 10 supports sheathing 11 which is nailed or otherwise secured in place. At spaced intervals along the siding 19 are nailed wind seal 12. Wind seal strips 12 are provided with a substantially rectangular base 13 which sets firmly against the siding. A rounded outer portion 14 projects from the base 13 and is provided with inward channel 15. The outwardly extending portion 14 is provided with rounded edge 17. The covering material or siding 19 may

be of any desired form, for example, tapered as shown in Figure 1. A groove or channel generally curved in form is located in the rear face of the covering material 19. The channel is adjacent the edge of the covering material and the channel defines two tongues 35 projecting toward each other outlining grooved walls 23 and 24 having a radius of curvature such that the grooved portion 17 of the wind seal strip fits therein.

In applying the seal strip 12 such strips are secured at desired intervals to the sheathing. The siding 19 is then adjusted so that that portion of 14 of strip 12 fits within the channel 15 in the siding and the grooved portion 18 fitting snugly against the grooved surface 23 or 24 with one of the projecting members 35 fitting snugly into channel 15. The covering material such as clap board 19 is then firmly secured in place by securing means such as means 25. It will be seen that when two clap boards are put in place, the securing means is completely covered as shown in Figure 1 and no nail holes are exposed for counter-punching, puttying and repointing.

It will be seen that the clap board is firmly held in place both at top and bottom and that the three points of wind and weather stoppage are obtained. One line of stoppage is at the butt end of the clap board along line 26. A second line is at the meeting of curved surface 23 and portion 17. A third line is at the meeting of a portion 35 with a shoulder of base portion 13 of wind seal strip 12. While these parts are shown spaced in Figure 1 this showing is merely for clearness so that the manner in which they interfit is evident. In actual practice there is line or surface contact between the parts at 26, 27 and 35 as described above. This effectively forms a three point seal. It will be noted also that between 26 and 27 there is a dead air space 29 which is of real value in construction of this type since here the energy of any air which may have gotten past seal 26 is dissipated and has a greatly decreased chance of getting past seal 27. The upper portion of Fig. 1 shows a second method of applying the lap-siding and also illustrates something of the flexibility of positioning provided.

In general it is desirable to have the tapered siding about some seven inches in width with a $\frac{3}{4}$ inch butt edge at the bottom where it is tapered and running to a $\frac{2}{16}$ inch at the top edge. Channel 20 is preferably about $1\frac{1}{8}$ inches in width and about one-quarter inch deep with $\frac{1}{8}$ inch shoulder. Wind seal strip 12 is con-

structed accordingly to fit channel 20. The above dimensions are merely directory and not limiting in any sense but have been found satisfactory. Where desired insulation may be employed and nails 34 may of course be screws or like fastening means. Present siding will not prevent cold weather, wind or insects from entering into the building principally since it is nailed only every sixteen or twenty inches which does not make for tightness. With the new construction it will be seen that there is a firm sealing means at the bottom of siding which is the point where the wind action is more serious. If desired the actual spaced construction shown at 28 in Fig. 1 may be used so that a wedging action is obtained which will make certain that a complete meeting at line 28 is obtained before any meeting is obtained at 28. This construction will allow for any possible non-uniformity in materials or warping thereof due to possible weathering effects. It is thought to be more important that the seal at 28 and 27 be attained than that 28 be open to the weather and 27 and 28 be closed. Special double groove and shoulder cutter is so constructed as to cut groove 23 and 24 with one operation. As stated this construction is suggested merely for those cases where less care is used to produce a uniform siding construction. The present disclosure is intended as illustrative and not limiting. Many alterations of construction may be made without departing from the spirit of the invention.

I claim:

1. In a wall construction comprising sheathing, siding material arranged in overlapping courses, one above the other, the siding in one course bearing at their upper margin against the sheathing, the said siding material having channels on its rear face near and substantially parallel with

the lower edge of the siding, the said channels partially closed by tongues projecting toward each other, and horizontal sealing strips secured to the sheathing and a portion of the said strip projecting into said channel, the said sealing strip of a configuration cooperating with the channels, and one tongue of each channel in forming a weather seal between adjacent courses of siding.

10 2. A siding panel comprising a substantially rectangular board having on the rear face and adjacent the lower edge a channel, the said channel defining tongues projecting towards each other from a constricted entrance to the channel and outlining curved walls, the combination of a sealing strip having a substantially rectangular base and a top portion wider than the base and the said top portion having a rounded shoulder cooperating with one of said tongues and the curved wall of the channel in forming a weather seal.

20 3. A wall construction comprising, a base material; siding material arranged in overlapping courses, one above the other; the siding material bearing at their upper margin against the base material, the said siding material having on its rear face, adjacent the lower edge a substantially horizontally extending channel, the said channel partially closed by tongues projecting toward each other and defining curved walls; a horizontally mounted sealing strip on the upper face portion of a lower course of siding cooperating with said channel in forming a weather seal between adjacent courses of the siding; the said sealing strip having a base and a top portion of greater width than the base of the strip, but of less width than the entrance to the channel.

HERBERT T. SEYMOUR.
